5 Claims. (Cl. 51—58)

This invention relates to a machine for grinding aspheric lenses, particularly large sized lenses.

One object of the invention is to provide a machine for grinding the optical surfaces of internal or external aspheric lenses. Another object is to provide a machine for grinding aspheric lenses which includes a nonrotating cutter blade accurately shaped on its cutting edge to the contour of the desired aspheric lens surface. Still another object is to provide means for longitudinal oscillation of said cutter blade. A further object is to provide an aspheric lens grinding machine in which the lens is rotated and the cutter blade is not rotated but is longitudinally oscillated.

These and other objects are attained by our invention which will be understood from the following description, reference being made to the accompanying drawing showing preferred forms thereof, in which

FIG. 1 is a side elevational view of one form of our invention for grinding external aspheric lens surfaces with parts broken away to show certain details in section;

FIG. 2 is a cross-sectional view taken on the line 2—2 of FIG. 1;

FIG. 3 is a fragmentary cross-sectional view taken on the line 3—3 of FIG. 2;

FIG. 4 is a fragmentary cross-sectional view taken on the line 4—4 of FIG. 1;

FIG. 5 is a fragmentary cross-sectional view taken on the line 5—5 of FIG. 1;

FIG. 6 is a side elevational view, with parts broken away, as shown in section, showing another form of our machine for grinding internal aspheric lens surfaces; and

FIG. 7 is a cross-sectional view of the same, taken on the line 7—7 of FIG. 6.

Referring to the drawings, particularly FIGS. 1 to 5, a work table 11 is attached by bolts 12 to a turntable 13, whose hub 14 is operatively attached to the vertical drive shaft 15 which is mounted at its lower end in a pillow block bearing 16, and also in a thrust bearing 17 which are disposed in operative position on a rigid frame 18. An intermediate bearing 16a attached to the frame 18 above the pulley 19 is also provided. Other bearings adjacent the upper extension of the shaft are provided and will be described later. Intermediate the bearings 16 and 16a, a drive pulley 19 is mounted on the shaft 15, the pulley being driven by the belt 20 which is actuated by a variable speed rotary power means (not shown).

The drive shaft 15 extends above the turntable 13 so that its upper end 22 is above the cutter frame 23, the latter being a platelike structure rotatably suspended on a steel ball bearing 29 positioned in a spherical cavity 30 in the upper end 22 of the shaft 15, as will be more fully explained below.

The cutter frame, numbered 23 generally, is a laminated structure comprising a front plate 24, a back plate 25, and a spacer 26 which holds the front and back plates apart, there being machine screws 27 at several locations for holding the laminated structure together. Portions of the spacer 26 are removed to form recesses for the cutter blade holders 46 and 47, and other parts as will be indicated.

The cutter frame 23 is disposed diametrically in relation to the drive shaft 15, and to the turntable 13 and the workpiece 10 (the lens blank) which is mounted

2

thereon. The cutter frame 23 is suspended on a steel ball 29 which is seated in a cavity 30 on the upper end of the drive shaft 15, by a saddle frame 31 whose lens 32 extend over the opposite sides of said cutter frame, enclosing bearing assembly 34 for the upper end portion of the drive shaft 15. A vertical adjusting screw 35 is vertically mounted in a threaded collar 38 on the saddle frame 31, there being a cavity 36 in the end of the screw to engage the steel ball 29, and a lock nut 37 on the screw to hold the screw in a selected vertical position.

The bearing assembly 34 consists of oppositely arranged mounting wings 39 which are disposed in a corresponding recess provided in the spacer 26 between the front and back plates 24 and 25 of the cutter blade frame 23, and attached thereto by through bolts 42. An upper sleeve bearing 40 and a lower sleeve bearing 41 are held in position on the drive shaft 15 by the edges of the wings 39.

The entire cutter blade frame 23 is prevented from rotating on the steel ball 29 by the abutment bracket 43 which is mounted on a top member of the machine frame 18.

The cutter blade holders 46 and 47 are substantially alike, being arranged in diametric alignment with relation to the work piece 10 and the work table 11. Each holder, for example 46, consists of a generally arcuate plate-like body which slidably fits between the front plate 24 and the back plate 25 in a recess provided by the spacer 26. The inner edge of the holder 46 (and 47) corresponds generally to the contour of the roughed-out work piece 10, and an arcuate diamond coated tool 49 is attached to the holder 46 (and 47). Longitudinal slots 77 and 78 are provided in the forward arcuate edges of the holders 46 and 47, and the diamond coated edge contoured tools 49 are held in accurately adjusted position by the shouldered screws 79 whose heads are recessed in holes on one wall of the slots, and threaded holes in the opposite wall bordering the slots 77 and 78. The front plate 24 at its lower outer corner is provided with an outwardly extending bracket 51 whose end surface abuts a micrometer screw 52 which is operatively mounted on boss 53 which is attached by screws 54 to the cutter blade holder 46 for the purpose of accurately measuring the depth of cut on the work piece.

The cutter blade holders 46 (left) and 47 (right) are supported for sliding movement laterally between the front plate 24 and the back plate 25, and are held against outward movement respectively by the feeder screws 56 and 57 which are mounted in threaded spacer blocks 58 and 59 held between the front plate 24 and the back plate 25. Lock nuts 60 and 61 are provided on the feeder screws 56 and 57 respectively. Tension springs 62 and 63 are provided respectively between the spacer blocks 58, 59 and the cutter blade holders 46 and 47.

The cutter blade holders 46 (left) and 47 (right) are supported vertically by the suspending spring 64 and 65 respectively which are attached respectively to the left and right mounting wings 39. The holders 46 and 47 are also positioned by the stops 66 and 67 respectively which are rectangular blocks mounted respectively on pivots 68 and 69 which are mounted by mounting plates respectively 70 and 71 (not shown) to the front and back plates 24 and 25, there being rectangular recesses respectively 72 and 73 in the cutter blade holders 46 and 47, which recesses are of larger dimensions than the stops 66 and 67.

The cutter blade holders 46 (left) and 47 (right) are oscillated in a direction tangential to the abrasive surface of the cutter blades or tools 49. The oscillating means, in general, consists of eccentrically mounted shafts on each holder, and means for rotating them. This means acts upon a rectangular follower block (which is confined

in a recess in the spacer for movement only at right angles to the oscillation movement), to move the holders in tangential oscillation. For each of the cutter blades 46 and 47, there is provided respectively shafts 81 and 82, which are each mounted in sleeve bearings 83 in the front plate 24 and back plate 25. An eccentric 85 is provided on the portion of the shafts between the plates 24 and 25, and a follower block 86 is mounted on the eccentric 85. A rectangular opening 87 in the holder 46 is provided to receive the follower block 86, the edges of this opening slidingly engaging the block on two sides, but permitting movement at right angles to the tangent to the curve of the cutter blades 49. Sprockets 88 and 89 are mounted respectively on the oscillating shafts 81 and 82 for the rotation thereof, both sprockets extending forwardly from the front face of the front plate 24. An electric motor 90, having means for speed reduction, is mounted on the edge of the cutter blade frame 23, a drive sprocket 91 projecting in driving alignment with the sprockets 88 and 89, a drive chain 92 being arranged to operatively pass over the motor drive sprocket, the shaft sprockets 88 and 89, and idler sprocket 94 mounted on the front plate 24 in position to provide an operable path for the chain drive 92.

The cutter blade or tool 49 consists of a metal base whose arcuate edge face is coated with diamond particles which are bonded together and to each other by an electroplate of nickel, the edge surface being formed during electroplating by a template whose curvature accurately coincides with the aspheric surface of the lens surface which is to be generated on the work piece.

Another form of this machine shown in FIGS. 6 and 7 may be used to generate an internal lens surface. An internal lens work piece 10A is mounted on a turntable 11A, as in the previously described machine form, and the work piece is rotated by means as previously described. The plate-like cutter frame 23A is suspended on a steel ball 29A from the top of the main drive shaft 15A. In the form shown in FIGS. 6 and 7 a single radial cutter frame 23A is mounted on sleeve bearings around the shaft 15A, and it consists of a front plate 24A, a back plate 25A, and a spacer plate 26A bolted together, with recesses in the spacer plate 26A for the cutter blade holder 46A, and other parts as will be described. As before, contoured diamond coated cutter or tool 49A is mounted by bolts in a peripheral groove in the cutter blade holder 46A. The cutter blade holder 46A is held in a rectangular stop 66A which is mounted on the pivot 68A in mounting plate (not shown but like 70) and is arranged to slide in a rectangular recess 72A in the spacer plate 26A. The tension spring 62A holds the lower end of the cutter blade holder 46A toward the shaft 15A, and the spring 64A which is attached to an upward extension 51A of the cutter blade holder 46A and to a bracket 101 on the suspending frame 31A. The cutter blade holder 46A and the cutter tool 49A are oscillated in a direction tangential to the cutting edge of the tool by means of an eccentric oscillating shaft 81A which is mounted in sleeve bearings in the front plate 24A and the back plate 25 of the cutter blade frame 23A. An eccentric (similar to 85) is provided in a portion of the shaft between the plates, and a follower block 86A is mounted on the eccentric. A rectangular opening (similar to 87) in the spacer plate 26A is provided to receive the follower block 86A, the edges of this opening slidingly engaging the block on two sides, but not permitting movement at right angles to the tangent to the curve of the contour cutter blade 49A. A sprocket 88A is mounted on the oscillating shaft 81A for its rotation, the sprocket extending forwardly from the front face of the front plate 24A. An electric motor 90A, having means for speed reduction, is mounted on the supporting frame 31A, a drive sprocket 91A projecting in driving alignment with the sprocket 88A, a drive chain 92A being arranged operatively over the motor drive sprocket 91A, the oscillating shaft sprocket 88A and an

idler sprocket 94A also mounted on the supporting frame 31A.

A feeder screw 56A is provided on the upper corner of the cutter blade holder 46A, a threaded block 58A being mounted on the back plate 25A and a lock nut 60A being provided. A micrometer 52 is similarly mounted so that accurate measurement of the amount of the cut on the work piece 10A may be made.

The manner of operating the lens grinding machine will be apparent from the above description. The spherical blank for the lens is rough shaped by conventional forming means, and is mounted, by cementing, on the work table 11, and after the finishing cuts have been made by the diamond coated contour tool in this machine, the surface is given a final polishing by conventional lens polishing procedures. Water or other cutting liquid may be supplied on the cutting area. The tangential oscillation of the cutter is regulated so that any cutting ridges are removed and a smooth surface is generated.

The objectives set forth in the beginning have been attained.

We claim:

1. A machine for grinding an aspheric lens surface on a lens work piece comprising a rigid supporting frame including a base and a platform disposed above said base; a vertical shaft mounted in bearings on said frame and extending above said platform; means for rotating said shaft; a turntable mounted axially on said shaft above said platform, said turntable being adapted to support and rotate said lens work piece attached thereto, said work piece having an axial hole therethrough for said shaft; a cutter blade frame including a suspending member mounted on a bearing adjacent the upper end of said shaft, means for preventing the rotation of said cutter blade frame in relation to said supporting frame; a cutter blade holder oscillatably mounted on said cutter blade frame; a contoured diamond-coated edge cutter blade attached to said holder; and means for oscillating said cutter blade holder and said contoured cutter blade in an arcuate direction relative to the aspheric lens surface of said work piece during the rotation and grinding of said work piece.

2. A machine for grinding an aspheric lens surface on a lens work piece comprising a rigid supporting frame including a base and a platform disposed above said base; a vertical shaft mounted in bearings on said frame and extending above said platform and having an axially aligned ball cavity in its upper end; means for rotating said shaft; a turntable mounted axially on said shaft above said platform, said turntable being adapted to support and rotate said lens work piece attached thereto, the work piece having an axial hole therethrough for said shaft; a cutter blade frame including a suspending member telescoped over the upper end of said shaft and suspended on a steel ball in the cavity in the upper end of said shaft, and a radial frame member attached to said suspending member, said suspending member including cylindrical bearings around said shaft; means for preventing the rotation of said cutter blade frame in relation to said supporting frame; a cutter blade holder oscillatably mounted on said radial cutter blade frame member; a contoured diamond-coated edge cutter blade adjustably attached to said holder; and means for oscillating said cutter blade holder and said contoured cutter blade in an arcuate direction relative to the aspheric surface of said work piece during the rotation and grinding of said work piece.

3. The machine for grinding aspheric lens surfaces as defined in claim 1, in which the means for oscillating the cutter blade holder consists of an oscillating shaft mounted for rotation on said cutter blade holder frame, said oscillating shaft having an eccentric portion engaging a follower-block positioned in a rectangular recess in said cutter blade holder frame, said recess being dimensioned to permit sliding movement of said block in a direction at right angles to the tangential direction of oscillatory movement, and rotary means including a motor mounted on

said cutter blade holder frame, a drive sprocket on said motor, a sprocket on said oscillating shaft, idler sprockets, and a chain operatively connecting said sprockets.

4. A machine for grinding an external aspheric lens surface on a lens work piece comprising a rigid supporting frame including a base, and a platform disposed above said base; a vertical shaft mounted on bearings on said frame and extending above said platform and having an axially aligned ball bearing cavity in its upper end; means for rotating said shaft; a turntable mounted axially on said shaft above said platform, said turntable being adapted to support and rotate work piece attached thereto, the work piece having an axial hole therethrough for said shaft; a cutter blade frame including a tubular suspending member telescoped over the upper end of said shaft and suspended on a steel ball in the cavity in the upper end of said shaft, and a pair of diametrically opposed radial frame members attached to said tubular suspending member, said suspending member including cylindrical bearings around said shaft; means for preventing the rotation of said cutter blade frame in relation to said supporting frame; cutter blade holders oscillatably mounted on each of said radial cutter blade frame members; contoured diamond-coated edge cutter blades attached to each of said holders; and means for simultaneously oscillating said cutter blade holders and said contoured cutter blades in an arcuate direction relative to the aspheric surface of said work piece during the rotation and grinding of said work piece.

5

10

15

20

25

5. The machine for grinding external aspheric lens surfaces as defined in claim 4, in which the means for oscillating each of the cutter blade holders consists of an oscillation shaft mounted for rotation on each of said radial frame members, said oscillating shaft having an eccentric portion engaging a follower block positioned in a rectangular recess in said radial cutter blade frame member, said recess being dimensioned to permit sliding movement of said block in a direction at right angles to the tangential direction of oscillatory movement, and rotary means including a motor mounted on one of said cutter blade frame members, a drive sprocket on said motor, a sprocket on each of said oscillating shafts, idler sprockets, and a chain operatively connecting said sprockets.
